(57) **CLAIM**

I claim the ornamental design for a tire, as shown and
described.

DESCRIPTION

FIG. 1 is a front view of my new design comprising a tire; and,
FIG. 2 is a side view of the tire shown in FIG. 1.

In the drawings, the broken lines defining tread groove elements,
the sidewall, inner bead and the peripheral boundary
between the claimed tire tread and the unclaimed sidewall
depict environmental subject matter that forms no part of the
claimed design.
